UNITED STATES PATENT OFFICE.

EDWARD E. ROSE, OF EDGEWOOD, AND OTTO P. SCHUSTER, OF NORTH IRWIN, PENNSYLVANIA, ASSIGNORS TO WESTINGHOUSE ELECTRIC AND MANUFACTURING COMPANY, A CORPORATION OF PENNSYLVANIA.

CONTROLLER.

Application filed September 8, 1921. Serial No. 499,264.

To all whom it may concern:

Be it known that we, EDWARD E. ROSE, a citizen of the United States, and a resident of Edgewood, in the county of Allegheny and State of Pennsylvania, and Otto P. SCHUSTER, a citizen of the United States, and a resident of North Irwin, in the county of Westmoreland and State of Pennsylvania, have invented a new and useful Improvement in Controllers, of which the following is a specification.

Our invention relates to controllers for governing the operation of dynamo-electric machines and it has particular relation to those employed for governing a plurality of motors such, for example, as are required for driving an electric locomotive.

One object of our invention is to provide a controller that shall be simple and economical in construction and positive and reliable in operation.

Another object of our invention is to provide interlocks for a plurality of control drums, whereby it shall be impossible to actuate certain of the drums when other drums occupy predetermined positions.

Briefly speaking, our invention consists in providing improved interlocks between the several control drums to effect a desired sequence of operation thereof and to prevent improper control-circuit relations.

For a better understanding of our invention, reference may be made to the accompanying drawings,

Figure 1 of which is a plan view of a controller embodying our invention;

Fig. 2 is a view, partly in side elevation and partly in section, of the controller shown in Fig. 1;

Figs. 3 and 4 are sectional views taken along the lines III—III and IV—IV, respectively, of Fig. 2;

Figs. 5, 6 and 7 are detail, plan, side and end views, respectively, of one of the pawls or interlocking members that are shown in Figs. 1 to 4, inclusive;

Figs. 8 and 9 are views, in plan and in side elevation, respectively, of another pawl or interlocking member in the controller that is illustrated in Figs. 1 to 4, inclusive.

Figs. 10, 11 and 12 are views, in plan, side and end elevation, respectively, of a third pawl or interlocking member that is

employed in the controller illustrated in Figs. 1 to 4, inclusive, of the drawing;

Fig. 13 is a cross-sectional view, taken along the lines XIII—XIII of Fig. 10; and

Fig. 14 is a plan view, partly in section, taken along the line XIV—XIV of Fig. 2, of an interlocking or cam member that is employed in the controller illustrated in Figs. 1 to 4, inclusive, of the drawing.

Referring particularly to Figs. 1 to 4, inclusive, a controller 1 has a supporting frame or case 2 and a cover 3, which is pivotally mounted upon the case 2 by a plurality of hinges 4. The cover 3 may be locked in its closed position by means of a latching device 5 (see Figs. 3 and 4). The controller 1 is provided with a reverse drum 6 that is adapted to engage a plurality of control fingers 7, a speed drum 8 for controlling a plurality of accelerating switches that govern the speed of a plurality of motors (not shown), a motor-combination drum 9 for changing the relation of the motors from series to series-parallel relation or from series-parallel to parallel relation, in accordance with the particular operating conditions of the control system, and a regenerative drum 10 that governs the motors during electrical braking.

The reverse drum 6 is securely mounted upon a shaft 11, which may be actuated by a reverser handle 12. The speed drum 8 is securely mounted upon the shaft 13, having a pinion 14 securely attached thereto at its upper end. The pinion 14 is actuated by a gear-wheel sector 15, which is mechanically connected to a speed handle 16 by a shaft 17, to which both are securely attached.

The motor-combination drum 9 is securely mounted upon a shaft 18, which is provided with a handle 19 at its upper end. The regenerative drum 10 is rotatably mounted upon the shaft 18 and has a pinion 21 secured to its upper end. The pinion 21 may be actuated by a gear-wheel sector 22, which is mechanically connected to a shaft 24. A suitable handle 23 is provided for the shaft 24. The shafts 11, 13 and 18 are rotatably mounted within the controller 1 by means of a plurality of lugs or supporting members 25, 26 and 27, respectively, which form a part of the case 2.

Referring particularly to Fig. 4 of the

drawing, the reverse-drum shaft 11 is provided with a cam or interlocking member 28 having a plurality of notches 30 and 31 corresponding to forward operation and reverse operation respectively, and having an intermediate projecting portion 29 provided with a notch 29a corresponding to the neutral or "off" position.

The regenerative drum 10 is provided with a cam or interlocking member 32 having a motoring notch 34 and a regenerative notch 35 which are separated by a projecting portion 36, as is best illustrated in Fig. 14 of the drawing.

The regenerative drum 10 is provided with a plurality of contact segments 37 that are adapted to engage a plurality of contact fingers 38 to effect energization of the actuating coils of a plurality of switches (not shown) for governing the main motor circuits during regeneration. The regenerative handle 23 is restricted by a stop member 23a from actuating the cam member 32 in a clockwise direction beyond the position illustrated by Figs. 1 and 2 of the drawing. The cam member 32 may be actuated in a counter-clockwise direction through a plurality of subordinate or accelerating positions corresponding to positions 1' to 9', inclusive, of the regenerative controller handle 23.

The speed drum shaft 13 is provided with a collar 39 having a recess 40, which normally occupies the illustrated position, corresponding to the "off" position of the speed drum. The speed drum 8 is provided with a plurality of contact segments 41, which are adapted to engage a plurality of control fingers 42a to establish circuits that energize the actuating coils of a plurality of accelerating switches (not shown) for governing the speed of the motors.

An interlock or pawl member 42 is pivotally mounted on a pin 43 that is positioned between the reverse drum 6 and the speed drum 8 of the controller 1. A plurality of pawl members 44 and 45 are pivotally mounted upon a pin 46 that is securely positioned between the speed drum 8 and the regenerative drum 10.

For a better understanding of the shape of the pawl member 42, reference may be made to Figs. 5 and 7 of the drawing. The pawl member 42 is provided with a pointed lug or projection 47 which co-operates with the reversing cam member 28, and a lug 48 that is adapted to fit in the recess 40 of the ring member 39 which is securely mounted upon the speed drum shaft 13. The pawl 42 is provided with a third lug 49 having a hole 51 therein, in which the pin 52 (see Fig. 4) may be mounted, and a hole 53 for holding a cotter-pin 54 to prevent longitudinal movement of the pin 52. The pawl 42 is so designed that the reversing cam member 28 can

be reversed only when the speed drum 8 is in the "off" position, as it is then that the lug 48 fits in the recess 40 of the ring 39.

When the reverse drum 6 is in its "off" position, the projection 29 of the cam member 28 so engages the projection 47 of the pawl member 42 that it is impossible to withdraw the lug 48 from the recess 40 of the ring 39, thus rendering it impossible to move the speed drum 8 from its "off" position.

The co-operating pawl member 44, which is illustrated by Figs. 8 and 9, has a lug 56 that is also adapted to fit in the recess 40 of the annular member 39 that is mounted upon the speed shaft 13.

At the other end of the pawl member 44, a projecting portion 57 is provided, having a hole 58 that is adapted to hold the pin 59, as illustrated in Fig. 4 of the drawing. Lugs 61 and 62 are provided on the pawl member 44 to limit its movement in a manner that will hereinafter be more fully described.

The pawl member 45, which is illustrated by Figs. 10 to 13, inclusive, comprises a projecting portion 63 in which a roller 64 is mounted upon a pin 65 (see Figs. 4 and 13). The pawl member 45 comprises a projection 66 having a hole 67 therein, in which the pin 52 is slidably mounted (see Fig. 4). The pawl member 45 is provided with a projecting portion 68 having a hole 69 therein, in which the pin 59 is mounted. A hole 70 is provided in the projection 68 for receiving cotter pin 71, which is illustrated in Fig. 4 of the drawing.

A plurality of lugs 72 and 73, constituting part of the pawl member 45, co-operate with the lugs 61 and 62, respectively, of the pawl member 44 to limit the relative movement, in both directions, of the pawl members 44 and 45.

A resilient member, such, for example, as a spring 75, is mounted upon the pin 52 between the projection 49 of the pawl 42 and the projection 66 of the pawl 45. The spring 75 biases the pawl members 42 and 45, respectively, against the corresponding cam members 28 and 32. The projections 57 and 68 of the pawl members 44 and 45, respectively, are normally maintained a relatively great distance apart by a resilient member, such, for example, as a spring 76, which is mounted upon the pin 59.

The lugs 61 and 72 of the corresponding pawl members 44 and 45 limit the relative movement of the pawl members 44 and 45. The lug members 61 and 72 are so disposed that, when the roller 64 fits into either the motoring notch 34 or the regenerative notch 35 of the cam member 32, the projection 56 of the pawl 44 will be clear of the recess 40 of the annular member 39 which is mounted upon the shaft 13.

When the roller 64 is in any other posi-

tion than notches 34 or 35, the pressure applied to the spring 76 by the projection 68 of the pawl member 45 will be transmitted to the projection 57 of the pawl member 44, thereby causing it to be actuated in a clockwise direction into the recess 40 of the annular member 39. This scissor-like arrangement of the pawl members 44 and 45 and their respective lugs 62 and 73 makes it

10 necessary to actuate the speed drum 8 to its "off" position prior to actuating the regenerative drum 10 from its first position.

If the regenerative drum 10 occupies any 15 of its regenerative positions, which are indicated by the characters 1' to 9', inclusive, upon the notch plate 78, the speed controller 8 can not be actuated from its "off" position, or if the controller 8 is returned to its "off" position, it is necessary to return the 20 regenerative drum 10 to its first position before again notching up the speed drum 8.

The projection 36 upon the cam member 32 is so designed that the roller 63 can pass over it only when the projection 56 of the 25 pawl member 44 is in the recess 40 of the annular member 39 that is attached to the speed drum shaft 13. The projections 62 and 73 of the pawl members 44 and 45, respectively, are so designed that they limit 30 the compression that can be applied to the spring 76 by the pawl members 44 and 45 and also their relative angular movement, thereby preventing the roller 64 from passing over the projection 36 of the cam member 32, when the speed controller 8 does not 35 occupy its "off" position.

The operation of the control system is begun by actuating the reverser handle 12 to either its forward or its reverse position, in 40 accordance with the direction of operation that is desired. When the reverser 6 occupies either its reverse or its forward position, the pawl member 42 is actuated in a clockwise direction by the spring 75 to disengage the projection 48 thereof from the recess 40 of the annular member 39, which is secured to the speed drum shaft 13.

The speed drum 8 may be actuated by 45 means of the speed handle 16 through its various accelerating positions, provided the regenerative controller 10 occupies its motoring position. When the speed drum handle 16 has reached its last position and the motors have attained a speed corresponding to that notch, the speed handle 16 may be actuated backwardly to its third notch, and the motor-combination handle 19 be actuated to change the connection of the motors from series-parallel to parallel relation or whatever other arrangement of the motors that the operating conditions require.

As the shaft 18 upon which the motor-combination drum 9 is mounted is not mechanically interlocked with the regenerative

controller drum 10, the shaft 18 can be actuated independently of the drums 6, 8 and 10. When the motor-combination drum 9 occupies the new position, the speed handle 16 may again be actuated to effect movement of the speed drum 8 in a manner that will effect further acceleration of the motors. 70

To effect regeneration of the motors under high speed conditions, it is necessary to 75 return the speed drum 8 to its "off" position and to actuate the regenerative drum 10 from its basic or primary motoring position to its first or basic regenerative position. This is effected by properly actuating the regenerative handle 23, thereby effecting movement of the gear-wheel sector 22 and the pinion 21. The roller 64 will pass over the projection 36 of the cam member 32, when the handle 23 is actuated, provided 80 the speed drum 8 is in its "off" position. After the regenerative drum 10 occupies its first or main position, the speed drum 8 may first be actuated through its various operating positions; and then the regenerative 85 drum may be operated through its secondary or subordinate positions 1' to 9', inclusive, by means of the regenerative handle 23, to vary the electrical braking effect of the motors, as desired. 95

Further regenerative braking may be effected by returning the regenerative drum 10 to its basic position and the speed drum 8 to its "off" position and then actuating the motor-combination drum 9 from its parallel 100 to its series-parallel position. The speed drum 8 may be again actuated through its operating positions, before actuating the regenerative drum 10 through its regulating or subordinate positions. 105

If the speed drum 8 is actuated to its "off" position, when the regenerative drum 10 occupies any but its first position, the speed drum 8 will be locked in its "off" position by the pawl member 44, until the 110 regenerative drum 10 has been returned to its first position.

From the above description, it is apparent that we have so provided a controller with interlocks that it is impossible for the operator to effect incorrect movement of one or more of the control drums with respect to the remaining drums. 115

While we have shown the apparatus embodying our invention in the preferred 120 form, it is apparent that minor modifications may be made in the shape and arrangement of parts of the controller without departing from the spirit of our invention. We desire, therefore, to be limited only by 125 the scope of the appended claims.

We claim as our invention:

1. In a controller, the combination with a plurality of rotatable cam members, each of said cam members being capable of oc- 130

cupying a plurality of positions, of two movably mounted arms, means for biasing one of said arms against one of said cam members, means for limiting the relative 5 movement of said arms, and means for biasing said arms in a predetermined angular relation.

2. In a controller, the combination with a plurality of rotatable cam members, each 10 of said members being capable of occupying a plurality of positions, of two pivotally mounted arms, means for biasing one of said arms against one of said cam members, means for limiting the relative movement 15 of said arms, and means for biasing said arms in a predetermined angular relation.

3. In a controller, in combination, a plurality of cam members, each of said 20 cam members being disposed to occupy a plurality of positions and means for controlling the sequence of operation of the cam members comprising an arm adapted to interlock two of the cam members, a plurality 25 of arms for interlocking another of the cam members to one of said two cam members, and resilient members interposed between selected pairs of said arms to effect their operation as the cam members are 30 operated in a predetermined order.

4. In a controller, in combination, a plurality of cam members, each of said cam members being disposed to occupy a plurality 35 of positions and means for controlling the sequence of operation of the cam members comprising a pivotally mounted member for interlocking one pair of said cam members, a plurality of pivotally mounted co-acting members for interlocking another 40 pair of cam members and resilient means for biasing said interlocking members in a predetermined relation as said cam members are operated in a predetermined order.

5. In a controller, in combination, a plurality of cam members disposed to occupy 45 a plurality of positions, control drums

adapted to be operated by said cam members, and means for controlling the sequence of operation of the cam members comprising a plurality of arms disposed to engage said 50 cam members and springs interposed between selected pairs of arms to effect an interlocking of the cam members as said cam members are actuated in a predetermined sequence.

6. In a controller, in combination, a plurality of cam members, drums disposed for actuation by said cam members and means for controlling the operation of the cam members comprising arms disposed to engage 60 the cam members, springs interposed between pairs of arms to urge them into engagement with the cam members, said springs being disposed to effect a predetermined operation of the arms as the cam 65 members are operated thereby to control the sequence of operation of said drums.

7. In a controller, in combination, a plurality of control drums, cam members connected to said control drums and means 70 for controlling the operation of said cam members including a pair of arms pivotally mounted between a pair of cam members, resilient means interposed between said arms adapted to effect a relative angular movement of said arms, stops carried by the arms to limit the angular movement, a single arm disposed between one of said pair of cam members and another of the cam members and resilient means interposed between 80 one arm of said pair of arms and said single arm, said resilient means being adapted to effect the operation of the arms as the cam members are operated, thereby controlling the sequence of operation of the cam members.

In testimony whereof, we have hereunto subscribed our names this 6th day of September, 1921.

EDWARD E. ROSE.
OTTO P. SCHUSTER.
